Atty.

UNITED STATES PATENT OFFICE.

J. FRANK WILCOMB, OF WORCESTER, MASSACHUSETTS, ASSIGNOR TO SPARTAN NEEDLE COMPANY, OF PROVIDENCE, RHODE ISLAND, A CORPORATION OF RHODE ISLAND.

KNITTING INSTRUMENT.

1,398,821.

Specification of Letters Patent. Patented Nov. 29, 1921.

Application filed April 10, 1920. Serial No. 372,946.

To all whom it may concern:

Be it known that I, J. FRANK WILCOMB, a citizen of the United States, and a resident of Worcester, in the county of Worcester and State of Massachusetts, have invented an Improvement in Knitting Instruments, of which the following description, in connection with the accompanying drawings, is a specification, like characters on the drawings representing like parts.

This invention relates to knitting mechanisms but more particularly to the knitting instruments thereof, said instruments being designed to produce the desirable results attainable with latch needles or with spring beard needles, especially the latter while the objectionable features so often, in fact invariably, resulting from the use of these types of needles will be avoided, and many new and desirable results will be secured as will hereinafter appear.

The invention consists in the combination and arrangement of parts set forth in the following specification and particularly pointed out in the claims.

In the accompanying drawings I have shown merely for purposes of illustration examples of knitting instruments embodying the features of this invention wherein:

30 Figure 1 is a side elevation of the instrument in its entirety;

Fig. 1^a is a transverse section taken on the line 6—6, Fig. 1;

Fig. 2 is a detail view of the functioning portions of the yarn drawing element and quill in their loop shedding positions and with respect to the edge of the needle cylinder as represented by the line a—a a section of fabric being shown supported by the yarn drawing member;

Fig. 3 is a view similar to Fig. 2 illustrating the yarn drawing element slightly raised;

Fig. 4 is a view similar to Fig. 2 illustrating the yarn drawing element and the quill raised to their highest yarn receiving positions;

Fig. 5 is a similar view illustrating the parts in position for the next step in the loop forming operation, that is with the beard shown depressed;

Fig. 6 is a similar view illustrating the instrument elements returned to their first positions wherein the old loop has just been shed from the needle;

Fig. 7 is a detail view of the functioning ends of a modified form of knitting instrument;

Fig. 8 is a section through a portion of a knitting head illustrating two knitting instruments of the type shown in Fig. 1, one in the upper and the other in the lower position with respect to a presser and web holder; and

Fig. 9 is a detail plan of a portion of the presser shown in Fig. 7.

In the drawings, referring particularly to Figs. 1 to 7 inclusive, 1 is the yarn drawing or yarn seizing element of the knitting instrument, consisting of a hook 2 provided with a resilient nib or spring beard 3 herein of the usual spring beard needle form. Furthermore said yarn drawing element has a tapered neck 4, a shank 5 and butt 6, by means of which latter the functioning of said yarn drawing element may, from time to time, be effected. The knitting instrument also embodies a quill 7 herein of channel-like construction in cross section and within which said yarn drawing element is arranged to slide. The quill 7 is provided with a loop penetrating member 8, in the present example consisting of a pointed nose 9 slightly inturned toward the neck of said hooked element to work within a groove 10 formed longitudinally of the back of said neck. The loop penetrating point or nose 9 is herein the extremity of the back or closed portion of said quill and co-operating with said point are loop expanding, spreading or shaping members 11 and 12, said latter members together forming what is herein designated a hump 16, the bulk of which is disposed upon the hook side of the neck 4 so as to form a nubate or eye within which the beard point 13 is buried when the loop is to be shed. These loop expanding members are preferably formed by inclining at 11' the opposite walls of said quill from said point 9 toward the beard of the yarn drawing element and terminating at said hump 16, said members being extended toward said beard in the present example to form a nubate sufficient in depth only to cover said point 13 of the beard 3 when said beard is in its depressed state as shown in Fig. 5. Said members 11 and 12 are of less depth from front to back than the normal opening or space between the beard point and the neck of the yarn drawing member.

110

It will be observed that I provide means to depress the beard to move the point thereof from a position normally outside the range of said loop spreading element, into the 5 range thereof, without causing the point of said beard to seat or come into contact with the neck of the yarn drawing member.

The members 11 and 12 which, as previously stated, constitute together with the 10 point 9 the loop penetrating and loop expanding members of the quill, are in the present example capable of expanding the loop upon each side of the beard sufficient to receive the point of the beard, but by extending far enough to accomplish this result said side walls will also the better serve 15 as means to prevent lateral displacement of the point of said beard while positioned between said walls, even though said beard be 20 made of exceedingly light material.

From the point of its greatest depth the side walls 11 and 12 of the hump are reversely inclined or curved at 19 to form what is herein termed a throat 20 provided 25 particularly to receive the old loop and separate it from the new yarn that is laid upon the other side of the hump 16 against the neck of the hook (see Figs. 4 and 5).

Where a positive independent movement 30 is to be given to the quill as well as to the yarn drawing member a butt 22 is provided and acted upon together with the butts 6 by means such for example as knitting cans, not shown, and herein I have formed such 35 a butt as a lateral extension of the sides of said quill and between these extensions and the adjacent portion of said quill a filler block 23 is inserted which constitutes a reinforcement for the portions of said side walls 40 that form said butt, also a guide for the shank of said yarn drawing member and, if desired, a stop for the butt 6 of said latter member. The two elements of the knitting instrument thus equipped may be operated 45 separately at will and, from time to time, to perform their various functions and for illustrating the most important of said functions Figs. 2 to 6 inclusive are provided. In Fig. 2 the loop forming portions of the instrument are shown below a line $a-a$ indicating the upper edge of the instrument carrier and these positions indicate said parts as they would appear immediately following the shedding of a loop, the web being suspended from the hook in the usual 55 manner.

Fig. 3 illustrates the next step in the knitting operation wherein the hook has been slightly advanced and the loop penetrating 60 nose of the sheath is in its position preparatory to being moved to penetrate said loop. The next step represented in Fig. 4 shows the two elements of the knitting instrument in their advanced positions, the loop penetrating element and the hump having been

passed through the old loop so as to place said loop within the throat 20 of the quill and new yarn is shown laid across the neck of the needle below the point 13 of the beard and resting against the inclined edges 70 11' of said quill. From this illustration it will be seen that the new yarn and the old loop are widely separated one from the other by the hump 16 thus providing a definite alinement of old loops and new yarn with 75 ample space for the beard of the needle to pass therebetween without causing injury to either of the yarns and without danger of pressing the beard ahead of the new yarn which would result in both the old loop and 80 new yarn being cast off at the same time, an incident common to knitting machines employing the regular spring beard needle because there is very little, and in some cases no definite line of separation between 85 the new yarn and the old loop.

Fig. 5 illustrates the next step in the operation of knitting wherein the point 13 of the beard has been moved into alinement with the hump 16 and depressed between 90 the walls 11 and 12 of said hump by means of a suitable presser 14 in preparation for the shedding of the loop herein shown resting within the throat 20, over the yarn held within the hook 2, and Fig. 6 illustrates the 95 instrument in a position subsequent to the movements that cause said loop to be shed and in this figure the old loop is shown supported by what previously was the new yarn but now the new loop which still retains 100 its engagement with the hook of the instrument.

The combining of the resilient nib or spring beard with the quill herein shown and described results in numerous advantages particularly over the well known spring beard needle, for example, the guiding of the yarn drawing element between the walls of the channel-like quill provides ample support for said yarn drawing element, permitting the latter element to be made of a very much smaller or finer wire in consequence whereof the bend of the hook may be made much smaller to facilitate shedding and still retain the usual opening 110 or space between the beard and the neck of the hook for the yarn to reeve therethrough.

The extending of the walls 11 and 12 along each side of the hook to form the hump 16 dispenses with the forming of a 120 nucate or eye in the needle stem and the consequent necessity of pressing the point of the beard solidly against the stem of the needle which, in the ordinary spring beard needle, is directly responsible for deadening 125 needle beards and destroying the contour of the beards, and consequently causing imperfections in the work. The constant pounding of the delicate point of the beard against the hard metallic surface of the needle stem 130

by the beard presser, causes said point to be bent or dulled and rough edges and indentations are produced in the neck of the needle which contacts the yarn that must be drawn thereover producing defective wales in a knitted fabric.

Where a quill such as herein described is used in connection with spring bearded yarn drawing elements the instruments so formed 10 may be used equally well in direct-feed or skein-fed machines without producing any of the objectionable results recited for the reason that only a slight depression of the beard is required, and hence the normal hook 15 opening and original needle beard contour will be retained indefinitely.

The desirability of the resilient or spring beard over the non-resilient beard hinges largely upon the result of the small quill 20 hump so that the loop expansion during the shedding thereof may be reduced to a minimum, but the hump should be large enough so that it will provide an opening in the loop that will receive the point of the beard 25 when said beard is slightly depressed.

In Fig. 7 I have illustrated a knitting instrument of a slightly different type of hook wherein 22' is the yarn drawing member including a substantially straight resilient or 30 spring beard 23' pointed at 24 with said point 24 disposed at the usual distance from the neck 25 of said yarn drawing instrument.

A quill 26 similar in construction to the quill hereinbefore described is mounted 35 upon and adapted to move relatively to said yarn drawing member, said quill having a hump 27 consisting of side walls arranged upon opposite sides of the yarn drawing member similar to the side walls 11 and 12 40 of the previous form. The quill 26 is also herein provided with a nose 28 arranged to move along the back of the yarn drawing member and for the purpose hereinbefore described.

As will be seen by referring to 45 Fig. 7 the point 24 of the beard of said instrument is normally outside of the range of the hump 27. Consequently any relative longitudinal movement between the quill and 50 yarn drawing member will not bury the point 24 thereof within the hump and therefore the beard would not enter the loop that has been penetrated and expanded over the end of the quill until the end thereof has been depressed. The depressing of the 55 beards of either of the types of instruments shown may be accomplished by various forms of pressers and in Figs. 8 and 9 I have illustrated as a matter of convenience one commonly termed a ring preser and to 60 properly illustrate this I have shown the knitting instrument of the form disclosed in Fig. 1 mounted within a groove 30 of a common type of needle cylinder 31 and arranged outside and substantially concentric 65 with said needle cylinder is the preser 14

herein constructed in the form of a ring 32. This beard preser is provided with a series of notches 33 in its inner periphery corresponding in number to the number of instruments used and through which the beards 70 of the needles are adapted to pass during knitting. The upper edge of the preser 32 is beveled at 34 and when said beveled portion is engaged by the point of the downwardly moving beard 3 of said instrument said beard will be depressed just far enough to cause the point 13 thereof to enter the space between the side walls of the hump 16, or in other words to pass through the loop that is being expanded or spread by 80 said hump. The ring 32 may be, and herein is, shown mounted above the web holders 35 upon the usual bed ring 36 carried by the needle cylinder 31 and having radial grooves 36' to receive the web holders. The ring 32 85 and the web holders are held in place by a cap ring 37. The proper alinement of the notches 33 with the needles is maintained by slots 32' provided in the under side of the ring 32 and into which slots portions of 90 the web holders project from the grooves 36' of said ring.

Obviously various results may be obtained in the character of knitting by employing hooks of various forms and in the same manner that such changes are effected in the ordinary spring beard needle machine.

It is evident that said loop penetrating member will, in the present example, engage the two sides of the loop near where said loop is entered and will continue to open said loop progressively from the initial point of engagement toward the hook side thereof. Therefore the loop will be spread, opened, shaped or expanded for the passage 105 therethrough of the hook and the new yarn held by said hook.

Within the scope and purpose of the present invention the instrument herein shown and described may be used either in crocheting, lace making or in knitting by hand or by machine and although I have referred to the work produced by the instrument shown as knitting, it is distinctly to be understood that such term includes not only knitting but crocheting, lace making and all like fabrics and while I have herein shown and described merely for illustrative purposes certain embodiments of my invention and have disclosed and discussed in detail the construction and arrangement incidental to such disclosure, it is to be understood that the invention is limited neither to the mere details or relative arrangement of parts nor to the specific applications herein shown 125 but that extensive variations from the illustrations may be made without departing from the principles thereof.

Claims:

1. A loop forming instrument comprising 130

two relatively slidable elements, one of said elements having a spring beard hook for seizing the new yarn and the other of said elements including means for penetrating 5 the old loop at the back of the first mentioned element and progressively engaging the sides of said loop toward the front of the needle to spread said old loop for the reception of the extremity of said spring 10 beard, and means for positioning the extremity of said beard within the range of said spread loop.

2. A knitting instrument comprising a hooked yarn drawing element having a resilient beard, means to penetrate the loop at the back of said yarn drawing element including two forwardly inclined walls between which the hooked element is arranged to slide, said walls being adapted to open 20 the loop for the reception of said beard and to provide lateral support for said beard, and means to press said beard between said loop opening walls.

3. A knitting instrument comprising a hooked yarn drawing element having a spring beard, a quill having a loop penetrating member at the back of the yarn drawing element and loop opening members of less depth than the opening between the beard 30 point and the neck of the yarn drawing member, said loop opening member extending forwardly from said loop penetrating member at opposite sides of said yarn drawing element adapted to initiate the opening 35 of said loop and means for pressing said beard into the range of said opened loop.

4. A knitting instrument comprising a hooked yarn drawing element having a spring beard, an element slidably embracing 40 the hooked element and having means to effect an initial expansion of the loop and to separate said loop from the new yarn, and means for pressing said beard into the range of said expanded loop.

45 5. In combination, a loop forming instrument including a resilient bearded yarn-drawing element and an independently movable loop penetrating and loop spreading element, and means to depress said beard 50 to move the point thereof from a position normally outside the range of said loop spreading element into the range thereof whereby the loop spread thereby may be shed from said beard.

55 6. In combination, a loop forming instrument including a resilient bearded yarn drawing element and an independently movable loop penetrating and loop spreading element, and means to depress said beard 60 to move the point thereof from a position normally outside the range of said loop

spreading means into the range thereof without causing the point of said beard to seat.

7. A knitting instrument comprising a spring bearded yarn drawing element, a 65 relatively movable loop engaging element having means to penetrate the loop at a point remote from that portion of the loop engaging the beard side of said yarn drawing element and to spread said loop toward 70 said beard, and a presser to depress said beard from a position normally outside the range of said loop spreading means into the range thereof whereby said loop may be shed from said yarn drawing element. 75

8. In combination, a knitting instrument comprising two relatively slidable elements, one having a hooked yarn drawing element and the other being a loop controlling element of channel form in cross section to 80 receive said yarn drawing element, said loop controlling element having the open side of the channel on the hook side of the yarn drawing element, and a presser to depress the extremity of the hook of said yarn drawing element from a position outside to one within range of the walls of the channel of the loop controlling element whereby the loop may be cast off over said hook. 85

9. In combination, a knitting instrument 90 comprising two relatively slidable elements, one having a hooked yarn drawing element and the other being a loop controlling element of channel form in cross section to receive said yarn drawing element, said 95 loop controlling element having the open side of the channel on the hook side of the yarn drawing element, and a presser to depress the extremity of the hook of said yarn drawing element from a position outside to one within range of the walls of the channel of the loop controlling element whereby the loop may be cast off over said hook, said channel shaped element having a throat to divide the old loop from the new yarn. 100 106

10. A loop forming instrument comprising a hooked yarn drawing element and a loop controlling element, the latter having a nose to penetrate the loop at the back of the hooked element and a wall at each side 110 of the hooked element rising on an incline from the nose and providing a two walled hump with a space between its walls adapted to receive the hook, said hook being of the spring beard type, and means for pressing 115 the beard into said space and toward the stem of the hooked element, substantially as described.

In testimony whereof, I have signed my name to this specification.

J. FRANK WILCOMB.
